CLAIM

The ornamental design for a collapsible bag with side gussets, as shown and described.

DESCRIPTION

FIG. 1 is a perspective view of the collapsible bag with side gussets showing the design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines illustrate portions of the collapsible bag with side gussets that form no part of the claimed design.
